Primary Examiner — Cynthia R Underwood

(74) Attorney, Agent, or Firm — EAGLE IP LIMITED

(57) **CLAIM**

The ornamental design for a hinge as shown and described.

DESCRIPTION

FIG. 1 is a front perspective view of a hinge, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another perspective view shown in a closed position; and,

FIG. 10 is another perspective view of another embodiment. The broken lines in the drawings depict portions of the hinge and form no part of the claimed design.

1 Claim, 10 Drawing Sheets
